UNITED STATES PATENT OFFICE

CHARLIE A. BROWN, OF CHRISTOPHER, ILLINOIS

MACHINE FOR REBABBITTING CONNECTING RODS

Application filed December 20, 1930. Serial No. 503,814.

This invention relates to machines for babbitting bearings and the general object of the invention is to provide a machine for babbitting bearings of connecting rods such as connecting rods used on internal combustion engines.

- A further object is to provide adjustable means whereby a core may be disposed within the fork or bearing of the connecting rod 10 and whereby the connecting rod may be accurately centered with relation to the core and held in place to permit Babbitt metal to run between the core and the inner face of the connecting rod bearing. 15 Another object is to provide fillet molding means adapted to be disposed on opposite sides of the connecting rod bearing to thus form fillets on the opposite sides of the Babbitt metal and provide means whereby the 20 fillet molding means may be shifted simultaneously toward or from the fork or bearing of the connecting rod.

Other objects will appear in the following description.

- 25 My invention is illustrated in the accompanying drawings, wherein:—

Figure 1 is a front elevation of a rebabbitting machine constructed in accordance with my invention;

30 Figure 2 is a top plan view thereof partly broken away;

Figure 3 is a side elevation thereof;

Figure 4 is a vertical section through the middle of the machine;

35 Figure 5 is a fragmentary horizontal section through the middle of the machine;

Figure 6 is a side elevation of the rod supporting dowels;

40 Figure 7 is an elevation of a modification of the rod supporting dowels.

Referring to these drawings, 10 designates a base and 11 a plate formed as a main casting of the jig and extending upward from the base. The plate 11 is formed at opposite ends with upwardly extending annular sockets 12 having set screws 13.

The plate 11 is recessed at 14 to receive two transversely movable blocks or slides 15 and 16. Passing through the plate 11 and disposed to extend outward between the blocks

are the screw pins 17. These have screw-threaded engagement in the plate 11 and extend into the recessed portion 14 and are disposed in superposed relation. Lock nuts 18 are engaged with said pins so as to hold them projected just the desired distance. The ends of the pins projecting away from the plate 11 are reduced in diameter. These pins are adapted to engage in a vertical groove formed in the flat face of an approximately semi-cylindrical core 19, the groove being designated 20. This core may be held in position by a movable bolt 21 extending through the back of plate 11 as shown in Figure 4. It is to be understood that a number of different sizes of cores 19 are designed to be used as will be hereafter explained, these cores varying in accordance with the sizes of the connecting rods. Each of the cores is formed at its upper end with a groove 22. 60 Slidable plates 15 and 16 are disposed to extend behind this core 19 and bear against the flat face thereof. The plates 15 and 16 are adjustable toward or from each other by means of cap screws 23 extending into the 65 plates through slots 24 formed in the back or plate 11. One of these plates, as for instance, the plate 16 has formed upon its upper face the graduated scale 25 which coacts with a zero mark 26 formed upon the back 70 piece 11. Thus this plate 16 may be adjusted with reference to this zero mark so as to 75 properly center the connecting rod.

Each of these plates 15 and 16 is provided with an outwardly projecting dowel pin, one 80 designated 26 and the other 27. The pin 27 is larger than the pin 26 and these pins as shown clearly in Figure 5 are designed to pass through the usual bolt openings *a* in the connecting rod A.

The pin 26 is relatively small and has a loose fit in one of the openings *a* while the pin 27 fits snugly within the opening but not so snugly but that the connecting rod may be easily put in place.

Also mounted upon the plates 15 and 16 are the laterally disposed clamps 28, these being mounted upon stud bolts 29 extending out from the plates 15 and 16. The clamps 28 are rotatable upon the stud bolts and are

freely movable inward and outward but are urged inward by the springs 30. Attached to each clamp 28 is a handle 31 which extends outward and is angularly bent at 32 so as to form a hook whereby the clamp may be rotated into or out of its clamping position and whereby it may be pulled outward against the action of the spring 30 to release the pressure of the clamp against the connecting rod and thus permit the clamp to be readily shifted. When in position, the clamps are turned inward and bear over the outer face of the opposite shoulders of the connecting rod as shown in Figure 5, thus holding the connecting rod in place with the dowel pins extending through the bolt apertures for the connecting rod.

Disposed above and below the connecting rod are the fillet molds which I have designated 33. These are formed upon their confronting faces as at 34 to form the fillet or bead in the Babbitt metal, which fillet projects out beyond the side face of the connecting rod. The fillet molding members 33 are each mounted upon a transversely extending bar. There are two of these bars, one for each fillet mold, the uppermost bar being designated 35, the lower bar being designated 36. These bars at their ends are enlarged as at 37 and apertured to receive the vertical posts 38 extending upward from the sockets 12, the posts being held in these sockets by the set screws 13.

Disposed between each pair of these heads 35 is a cam 39. Each cam is mounted upon a horizontal shaft 39^a. Each cam or rather the shaft of the cam is provided with a radially extending arm 40, these arms extending downward and being connected by a connecting rod 41 for simultaneous movement. Upon the shaft of one cam, there is disposed a handle 42 whereby the cams may be simultaneously operated. When the cams are turned in one position, they permit the bars 35 and 36 to move toward each other and when the cams are turned in another position, they shift the bars 35 and 36 away from each other. Springs 43 supported against collars 44 bear against these heads 37 and the bars and urge the bars toward each other and toward the cams 39. Thus it will be seen that when the handle 42 is turned upward, the cam will permit the two bars to move toward each other and when the handle is turned downward, the cam will be turned through a quarter of a revolution and the bars will be shifted away from each other. This will carry the fillet molding members 33 away from each other or cause them to move toward each other and into position against the lateral faces of the connecting rod bearing. The fillet molding members 33 are held in position by pivoted clamps 46, each pivoted at 47 upon one of the bars 35 and 36. The middle of each clamp is bowed at 48 to

accommodate the curvature of the fillet molding members. Each clamp 46 at its free end is notched at 49 to engage a stud 50 mounted upon the corresponding bar 35 or 36. When these clamps are in place, they hold the fillet molding members firmly in place and into engagement with the bars 35 and 36.

In the operation of this device, the diameter of the bearing in the connecting rod is measured and the proper core 19 is selected to fit this bearing.

In actual use, nine different sizes of cores are used for the different sizes of rods. It is obvious that a greater or less number of different sized cores may be used.

The dowel pins 26 and 27 are made in three sizes, that is, three-eighths, seven-sixteenths and one-half inch, but all of these dowel pins are one-half inch in diameter where they screw into the sliding blocks 15 and 16. The scale 25 may be on the frame of the machine and the zero mark 26 on one of the slide blocks. The dowels can be put in from the front or back and can be entirely removed. This is of particular value when rods like the Ford A connecting rods which have bolts made solid with the rod are being rebabbited. In these cases, the bolts can pass through the half-inch holes where the dowels were. It is to be particularly noted, however, that the dowels of each pair are of different sizes, one of the dowels having a loose fit and the other dowel having a snug or running fit. Thus one of the dowel pins fits in the rod loosely and the one on the sliding block 16 has a running fit. The rod to be poured is measured from the centers of the bolt holes. We will assume that the distance between the bolt holes is 2½ inches. The lock bolt on the back of the sliding block 16 is loosened and this block or slide is shifted so as to bring the 2½ inch mark on the scale 25 in line with the zero line 26 on the frame. The other slide block is then pulled over to where the smaller sized dowel 26 will line up with the hole in the rod and the rod is slipped upon these dowels and clamped thereon. The reason for the use of the small dowel 26 is that it allows the rods that are not machined perfectly true with respect to the bolt holes to seat themselves between the fillet dies or molds and also because it has been found that on the same make of rods, there is oftentimes a slight difference between the distance of the bolt holes which would make it hard to get the rod off or on the machine unless one of the dowels is relatively small in diameter. After the rod is put in place and properly clamped, the handle 42 is shifted so as to shift the cams 39 and permit the two bars 35 and 36 to move toward each other, bringing the fillet molds or dies down into position against the upper and lower faces of the rod. The Babbitt metal is then poured. When it is hardened sufficient-

ly, the handle 42 is operated to force the two bars 35 and 36 away from each other, carrying the fillet dies or molds away from each other, the rod holding members 28 are then pulled out against the action of the springs 30 and rotated out of their holding position and the connecting rod is removed.

Attention is called to the fact that the fillet dies or molds 33 are inserted in place downward behind the bar 35 and upward behind the bar 36. Thus it is easy to put them in and they are held solidly and are easily adjusted in place on rods that have uneven faces. These fillet molds or dies 33 are held in place by the swinging latches 46 but there is a small amount of spring or give in the parts that hold the fillet molds in place so that these molds may seat on uneven rods either sidewise or from front to back.

It is to be understood that I contemplate nine sizes of cores 19 and that there are nine sizes of fillet dies 33 to fit the different cores, the bottom one, of course, fitting close against the core as illustrated in Figure 4 while the top fillet die is the same in all respects as the bottom fillet die except that it is poured out about one-fourth of an inch larger so as to form a pouring opening 22 with a slight taper to it so as to draw off the babbitt easily.

While in Figure 5 I have illustrated the dowel pins 26 and 27 as being straight pins, screw-threaded at their inner ends for insertion into the slides 15 and 16, I preferably form the dowel pins as illustrated in Figure 6. These dowel pins are all precisely half an inch in diameter where they screw into the slides 15 and 16 and these dowel pins might be screwed in either from the front or back, though I have illustrated them as screwing in from the front but each dowel pin is reduced in diameter at its projected end as shown in Figure 6, the projecting portion of the dowel pin 26 being less in diameter than the projecting portion of the dowel pin 27 for the reasons hereinbefore stated. The shoulder at the juncture of the dowels and the base portion thereof should come even with the front faces of the slides 15 and 16.

In Figure 7, I illustrate a dowel pin 27^a which may be used in place of the dowel pin 27 (and the same construction, of course, will apply to the construction 26) in which the dowel pin 27^a may extend through the slots 24 in the back plate 11, and pass through screw-threaded openings in the slide 16, thus doing away with the necessity of using the screws 23. Thus the dowel pin 27^a will take the place of the screw 23 and the dowel pin 27 inasmuch as the shoulder on this pin will bear against the rear face of the back plate 11 and the shoulder on the front end of the pin will just come through to the face of the slide 16. This form of dowel pin is to be used with the slides 15 and 16 both and the projections of

the dowel pins will have the same difference in diameter as before adverted to.

While I have illustrated a machine in which all of the parts have been designed to secure particular effectiveness, I do not wish to be limited to these details, as obviously these might be modified in many ways without departing from the spirit of the invention as defined in the appended claims.

I claim:—

1. A machine for rebabbing connecting rods including a vertical supporting plate, opposed slides carried on the supporting plate and adjustable toward or from each other and each having an opening for a removable dowel pin, means on the supporting plate for removably supporting a vertically disposed semi-cylindrical core in front of the plate and between the dowel pin openings, means for clamping a connecting rod with its bearing disposed concentric to the core and its bolt holes in alignment with the openings for the dowel pins, upper and lower fillet molds, transversely extending bars upon which the fillet molds are mounted, vertical posts extending through said bars, springs urging the bars toward each other, and rotatable cams whereby the bars may be shifted away from each other against the action of the spring.

2. A machine for rebabbing connecting rods including a vertical supporting plate, opposed slides carried on the supporting plate and adjustable towards and from each other and each having an opening for a removable dowel pin, means on the supporting plate for removably supporting a vertically disposed semi-cylindrical core in front of the plate and between the dowel pin openings, means for clamping a connecting rod with its bearing disposed concentric to the core and its bolt holes in alignment with the openings for the dowel pins, upper and lower fillet molds, transversely extending bars upon which the fillet molds are detachably mounted on the bars, the bars at their extremities having eyes, vertical posts extending through the eyes of said bars, a cam mounted between the eyes on each post, manually operable means for rotating said cams to shift the bars toward or away from each other and carry the fillet molds into or out of operative position, springs surrounding the posts and bearing against the eyes of the bars, and adjustable means for tensioning the springs.

3. A machine for rebabbing connecting rods including a vertical supporting plate, opposed slides carried on the supporting plate and adjustable toward or from each other and each having an opening for a removable dowel pin, means on the supporting plate for removably supporting a vertically disposed semi-cylindrical core in front of the plate and between the dowel pin openings, means for clamping a connecting rod with its

bearing disposed concentric to the core and its bolt holes in alinement with the openings for the dowel pins, upper and lower fillet molds, transversely extending bars upon which the fillet molds are detachably mounted 5 on the bars, the bars at their extremities having eyes, vertical posts extending through the eyes of said bars, a cam mounted between the eyes on each post, each cam having an arm, a rod connecting said arms, and a lever mounted upon one of said cams whereby 10 it may be rotated.

4. A machine for rebabbitting connecting rods including a vertical supporting plate, 15 oppositely disposed slides slidably mounted upon the supporting plate and adjustable toward or from each other, each having an opening for a dowel pin, dowel pins disposed in said openings but removable therefrom, 20 means on the supporting plate for removably supporting a vertically disposed semi-cylindrical core in front of the plate and between the dowel pins, means for clamping a connecting rod with its bearings in position concentric to the core and with its bolt holes in 25 alinement with and engaged by said dowel pins, upper and lower fillet molds, vertically movable means for supporting said fillet molds, springs urging the supporting means 30 for the fillet means toward each other, and manually actuatable means for shifting the fillet mold carrying means simultaneously away from each other against the action of 35 said springs.

5. A machine for rebabbitting connecting rods including a vertical supporting plate, opposed slides carried on the supporting plate and adjustable toward or from each other, each of said slides carrying a connecting rod engaging means and each slide having 40 an opening for a removable dowel pin, dowel pins removably disposed in said openings, one of the dowel pins being sufficiently small to fit loosely within the bolt opening 45 of the connecting rod and the other fitting in the corresponding bolt opening, means on the supporting plate for removably supporting a vertically disposed semi-cylindrical core in front of the plate and between said 50 dowel pins, upper and lower fillet molds vertically movable into position against the upper and under surfaces respectively of the connecting rod, means for clamping said fillet molds in place, and means for simultaneously shifting said fillet molds toward or away 55 from each other and the connecting rod.

6. A machine for rebabbitting connecting rods including a vertical supporting plate recessed upon one face, opposed slides mounted 60 in the recess of the supporting plate, the slides being adjustable toward or from each other, and each having a dowel pin opening, dowel pins removably disposed in said openings, one of the pins being relatively small to 65 have a loose fit within the bolt opening of a

connecting rod and the other having a sliding fit in the corresponding bolt opening stud bolts projecting from the slides, each having a rotatable clamping head mounted thereon provided with a handle, springs surrounding the stud bolts and bearing against the clamping heads to urge them inward into clamping engagement with the opposed shoulders of the connecting rod, means on the supporting plate between the slides for removably supporting a vertically disposed semi-cylindrical plate in front of the core and between the dowel pins, upper and lower fillet molds, transversely extending bars supporting said fillet molds, posts passing loosely through the extremities of said bars, cams, one disposed between the like ends of the bars, manually operable means for simultaneously rotating said cams to simultaneously force the ends of the bars away from each other, and springs surrounding the posts and bearing against the ends of the bars and urging the bars toward said cams, the springs being adjustable as to tension.

7. A machine for rebabbitting connecting rods including a vertical supporting plate, opposed slides carried on the supporting plate and adjustable toward or from each other in a horizontal plane, the slides carrying movable dowel pins, adapted to be disposed through bolt holes of a connecting rod bearing, stud bolts mounted upon the slides, connecting rod clamping heads loosely mounted upon the stud bolts and each having a handle whereby it may be rotated, springs on the stud bolts urging the clamping heads inward against the end of the connecting rod when the dowel pins are disposed through the bolt holes of the connecting rod, a vertically disposed semi-cylindrical core detachably mounted upon the supporting plate between said dowel pins, vertically extending posts disposed opposite each end of the plate, upper and lower transversely extending bars through the ends of which said posts loosely pass, cams mounted between the opposed faces of the ends of said bars, manually operable means for simultaneously oscillating said cams to force the bars apart or permit them to move toward each other, springs surrounding the posts and urging the ends of the bars toward each other and against the cams, each of said bars being recessed at its middle to receive a fillet mold, the mold having a flange bearing against the bar, and a locking member pivoted upon each bar for movement in a horizontal plane, and when closed in parallel relation to the bar engaging over the end of the fillet mold and holding it in place, each of the locking members being bowed outwardly at its middle to conform to the semi-circular contour of the fillet molds.

8. A machine for rebabbitting connecting rods including a vertical supporting plate recessed upon one face, opposed slides mounted

in the recess and adjustable toward or from each other and each having a dowel pin, stud bolts projecting from the slides, each having a rotatable clamping head mounted thereon and provided with a handle, springs surrounding the stud bolts and bearing against the clamping heads to urge them inward into clamping engagement with the opposed shoulders of the connecting rods, upper and lower fillet molds, transversely extending bars supporting said fillet molds, a post passing loosely through the extremities of said bars, cams each disposed between the like ends of the bars, manually operable means for simultaneously rotating said cams to simultaneously force the ends of the bars away from each other, and springs surrounding the posts and bearing against the ends of the bars and urging the bars toward said cams.

9. A machine for rebabbing connecting rods including a vertical support, opposed slides carried on the support and adjustable toward or from each other, each slide carrying a connecting rod engaging means and an outwardly projecting dowel pin, means on the support for removably supporting a vertically disposed semi-cylindrical core in front of the support and between said dowel pins, upper and lower fillet mold supporting members, vertically disposed guide rods with which the ends of the fillet mold supporting members slidably engage whereby the fillet mold supporting members may be shifted vertically toward or from the connecting rod, means for clamping the fillet molds in place on the fillet mold supporting members, and manually operable means for simultaneously shifting both of said fillet mold supporting members at opposite ends toward or away from each other.

In testimony whereof I hereunto affix my signature.

CHARLIE A. BROWN.
